US00D975658S

(12) **United States Design Patent** (10) Patent No.: **US D975,658 S**
(45) Date of Patent: ** *Jan. 17, 2023

(54) **CONTROL DEVICE**(71) Applicant: **Lutron Technology Company LLC**,
Coopersburg, PA (US)(72) Inventors: **Elliot G. Jacoby**, Glenside, PA (US);
Jason C. Killo, Emmaus, PA (US);
Brad Michael Kreschollek, Bethlehem,
PA (US); **Noel Mayo**, Philadelphia, PA
(US)(73) Assignee: **Lutron Technology Company LLC**,
Coopersburg, PA (US)

(*) Notice: This patent is subject to a terminal disclaimer.

(**) Term: **15 Years**(21) Appl. No.: **29/812,628**(22) Filed: **Oct. 22, 2021**

FIG. 1 is a perspective view of a control device showing our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a control device showing a second embodiment of our new design.

FIG. 8 is a front view thereof, left side, right side, top, and bottom views, respectively, of the second embodiment being identical to the left side, right side, top, and bottom views of the first embodiment.

FIG. 9 is a perspective view of a control device showing a third embodiment of our new design.

FIG. 10 is a front view thereof.

FIG. 11 is a left side view thereof.

FIG. 12 is a right side view thereof.

FIG. 13 is a top view thereof.

FIG. 14 is a bottom view thereof.

FIG. 15 is a perspective view of a control device showing a fourth embodiment of our new design; and,

FIG. 16 is a front view thereof, left side, right side, top, and bottom views respectively, of the fourth embodiment being identical to the left side, right side, top, and bottom views of the third embodiment.

The rear views form no part of the design and are omitted. The dashed broken lines depict structure or features which form no part of the claimed design. The dot-dash broken lines depict boundaries which form no part of the claimed design.
